US0D1080671S

(12) **United States Design Patent** (10) **Patent No.:** **US D1,080,671 S**
(45) **Date of Patent:** **** Jun. 24, 2025**

(54) **DISPLAY SCREEN OR PORTION THEREOF WITH GRAPHICAL USER INTERFACE**

(71) Applicant: **Brava Home, Inc.**, Redwood City, CA (US)

(72) Inventors: **Andrey Baygulov**, Portland, OR (US); **Rory Starks**, Mountain View, CA (US); **Jean Nguyen**, San Francisco, CA (US)

(73) Assignee: **Brava Home, Inc.**, Redwood City, CA (US)

(**) Term: **15 Years**

(21) Appl. No.: **29/848,932**

(22) Filed: **Aug. 5, 2022**

Related U.S. Application Data

(63) Continuation of application No. 29/779,473, filed on Apr. 19, 2021, now Pat. No. Des. 960,188, which is a continuation of application No. 29/655,984, filed on Jul. 10, 2018, now Pat. No. Des. 916,772.

(57) **CLAIM**

The ornamental design for a display screen or portion thereof with graphical user interface, as shown and described.

DESCRIPTION

FIG. 1 is a front view of a display screen or portion thereof with graphical user interface showing our new design according to a first embodiment; and,

FIG. 2 is a front view of a display screen or portion thereof with graphical user interface showing our new design according to a second embodiment.

The outermost broken line rectangle showing a display screen or portion thereof, and all other broken lines showing portions of the graphical user interface, illustrate portions of the article of manufacture and form no part of the claimed design.

1 Claim, 2 Drawing Sheets
